UNITED STATES PATENT OFFICE.

THOMAS W. STONE, OF FORT WAYNE, INDIANA, ASSIGNOR TO WESTERN GAS CONSTRUCTION COMPANY, OF FORT WAYNE, INDIANA, A CORPORATION OF INDIANA.

VALVE-CONTROL MECHANISM.

1,353,977.

Specification of Letters Patent. Patented Sept. 28, 1920.

Application filed July 21, 1919. Serial No. 312,294.

To all whom it may concern:

Be it known that I, THOMAS W. STONE, a citizen of the United States, residing in Fort Wayne, in the county of Allen and State of Indiana, have invented a new and useful Improvement in Valve-Control Mechanism, of which the following is a specification.

This invention relates to a valve control mechanism for gas making machines, or apparatus, and has one especially valuable application in a water gas machine. It will be understood, however, that the invention is capable of other valuable applications than the specific use herein-mentioned and described in the ensuing specification.

A highly important object of the invention is the provision of a unitary manually-controlled means for opening the blast valve which controls the blast to the generator, and subsequently opening the stack valve, thereby permitting the stack valve to open shortly after the generator blast is opened and effecting a saving of the entire volume of gas in the machine at the time when the generator blast is turned on. At the completion of a run, there is present in the entire machine a large volume of good gas, and if the stack valve be opened at exactly the same instant as the generator blast, the good gas would be blown by the blast out the stack and consequently would be wasted. The present improved manually-controlled means permits this good gas to be blown back through the water seal into the scrubber and condenser, instead of out the stack, and at the same time insures opening of the stack valve before the blast can reach the water-seal and mingle with the gas in the scrubber and condenser. It is highly important that the blast of air be prevented from entering the scrubber or condenser, as this would produce an explosive mixture in the scrubber and condenser, with probable disastrous results.

Another object of the invention is the provision of means for effecting a finely adjusted control of the blast to the carburetor, thereby insuring a proper proportion of air in the carburetor to the incompletely consumed gas discharged from the generator, at the time when the generator blast is opened.

Another object of the invention is the provision of an exceedingly simple and effi-

cient interlock for the various valve control levers which absolutely prevents operation of any or all of said levers other than in a predetermined successive order in conformity with the exigencies of proper operation of a gas making machine.

With the above and other objects in view, the invention consists in certain novel arrangements, constructions and combinations of parts hereinafter described in a preferred form and particularly pointed out in the claims at the end of the specification.

In the drawing:

Fig. 1 is a diagrammatic elevational view of a water gas machine equipped with a valve control mechanism constructed in accordance with the present invention.

Fig. 2 is a diagrammatic plan view of the apparatus illustrated in Fig. 1.

Fig. 3 is a plan view of the control lever station.

Fig. 4 is a side elevation of the same.

Fig. 5 is a vertical section taken in a plane indicated by the line 5—5 of Fig. 4.

Fig. 6 is a fragmentary enlarged horizontal section taken in a plane indicated by the line 6—6 of Fig. 5.

Fig. 7 is a fragmentary enlarged horizontal section taken in a plane indicated by the line 7—7 of Fig. 5.

In the illustrated embodiment of the invention, the valve control mechanism is especially adapted for use in connection with a water gas machine, and for convenience the present description of the valve control mechanism will be confined to this use of the invention. Features of construction of the valve control mechanism are, however, readily susceptible of other valuable applications and it is manifest that the scope of the invention is by no means confined to the specific use and specific embodiment herein described.

Referring to the drawing and more particularly to Figs. 1 and 2, there is shown a water gas machine, or set, which embodies in its construction the following essential elements: A generator 11 provided with the usual chamber for carbonaceous fuel is connected by means of a pipe nipple 12 with a carburetor 13 and the latter in turn is connected by a passage-way 14 with a superheater 15. The carburetor and superheater

are of the well-known constructions embodying essentially two chambers filled with checker brick for storing up heat while the blast is on, which heat is utilized in the gas carburation and mixing in the subsequent run. Any suitable means for supplying oil or other gas enriching media to the carbureter may be employed. At the top of the super-heater there is provided a discharge pipe 16, having a branch 17, the latter leading to a water seal 18. The water seal 18 is in turn connected by means of a discharge pipe 19 with a scrubber 20, see Fig. 2, and said scrubber 20 is connected by a pipe nipple 21 with a condenser 22. The top of the discharge pipe 16 leading from the super-heater may be opened and closed by a stack valve 23. Said stack valve 23 consists essentially of a cover-plate 24 adapted to fit over the top of the discharge pipe 16 and pivoted at 25 in a suitable upright 26. Connected with the cover-plate 24 at its pivotal point is an operating link 27, the opposite end of which is pivoted to the upper end of a pressure-operated piston 28. The piston 28 is provided with the usual head, not shown, which works in a cylinder 30 and responds to pressure supplied to the upper end of the cylinder 30 to open the stack valve 23 and conversely to pressure supplied to the lower end of the cylinder to close said stack valve. Above the discharge pipe 16, is positioned a stack 31 through which the gases and products of combustion from the super-heater pass when the stack valve 23 is opened.

The generator 11 is constructed so as to be capable of up and down runs, that is to say when on the up run the steam passing through the mass of glowing fuel in the generator enters from the bottom and the gas generated as a result of the chemical reaction between the steam and the glowing fuel discharges from the top; whereas, on the down run, the steam enters at the top of the generator and the resultant gas discharges from the bottom. This change in direction of flow of the gas in the generator is effected by means of the main or up and down run valve 32. Said valve 32 embodies in its construction a pressure cylinder 33, within which works the usual piston, not shown. The valve piston, it will be understood, controls a port in the pipe nipple 12, and a second port in communication with the vertical pipe 34, the latter being connected by means of a short pipe union 35 with the lower end of the generator chamber. When the piston in the cylinder 33 is in the down position, as viewed in Fig. 1, the pipe union 12 is open to permit passage from the upper portion of the generator into the carbureter and concurrently the vertical pipe 34 is shut off from the generator to prevent passage of gas from the lower

end of the generator. Extending horizontally of the machine is a blast pipe 36 which leads to the vertical pipe 34 and is connected therewith at a point located just above the short pipe union 35. Also connected with the main blast pipe 36 is a branch 37 leading to the carbureter 13. Separate valves are provided for controlling the blast supplied by the pipe 36 to the generator and to the carbureter, namely: A generator blast valve 38 and a carbureter blast valve 39. Both of these valves are preferably of the gate type respectively provided with cylinders 40 and 41, having pistons which in the up position operate to open the valves 80 and which in the down position operate to close the valves.

In a water gas machine, as above constructed, the cycle of operation is as follows: The up and down run valve 32 is operated to the up-run position; the stack valve 23 is opened to permit the gases from the super-heater to pass through the stack; the generator blast valve 38 is open permitting the blast to pass into the bottom of the generator; the carbureter blast valve 39 is open to admit secondary air to the carbureter. With the valves in the above stated position, the operation continues for approximately four or five minutes and during this cycle of 95 the operation the hot gases and products of combustion from the generator pass out of the top of the generator into the carbureter, where any unconsumed, or partially consumed, portion of the gas is burned in the 100 secondary air supply by the carbureter blast. The whole volume of the hot products of combustion passes through the checker brick in the carbureter and through the super-heater to the stack, thereby storing up in the 105 carbureter and super-heater a great amount of heat for the subsequent run. As soon as the blast cycle of the operation is completed, the next portion of the cycle is carried out, this being generally known as "taking off the 110 blast and putting on the run." The carbureter blast valve is closed; the generator blast valve is closed; the stack valve is closed; as the main valve is in the up-run position, steam is admitted under the fire in 115 the generator through the steam pipe 111 so that the gas passes out of the top of the generator into the carbureter where it is enriched by oil which thoroughly volatilizes and intermixes with the lean gas from the 120 generator, as the mixture passes through the hot checker brick in the carbureter chamber and super-heater chamber. Finally the gas discharges through the outlet 16 and the branch 17 to the water seal 18 from which 125 it passes to the scrubber 20 and condenser 22. If the run be a down run, the operation is exactly similar, with the exception that the main valve is in the down-run position and the steam is admitted to the upper end of 130

the generator chamber through the steam pipe 112 with the result that the lean gas passes out the lower end of the generator into the vertical pipe 34 and subsequently 5 into the upper end of the carbureter chamber. At the end of the run the above described cycle of operation is repeated, that is a shift is made which is called "taking off the run and putting on the blast." This 10 is accomplished by shutting off the steam; opening the stack valve; opening the generator blast valve; opening the carbureter blast valve; the blast operation then proceeds as heretofore stated.

15 In the operation of a water gas machine according to the above cycle, it is important that the up and down run or main valve be always in the up-run position before the stack valve, the generator blast valve and the 20 carbureter blast valve be opened. Similarly it is important that the stack valve be in the open position approximately concurrently with the opening of the generator blast valve, and that in turn the generator blast 25 valve be in the open position before the carbureter blast valve is opened. Conversely it is important that the carbureter blast valve be closed before the generator blast valve and also the generator blast valve 30 before the stack valve is closed. These considerations are absolutely essential to the safe manipulation of the machine for the obvious reason that if any of the blast valves be opened for any appreciable extent while 35 the stack valve is closed, the blast will be blown back into the scrubber and condenser where it will mix with the gas and form an explosive mixture.

40 While safety in operation demands that the stack valve be opened before the blast valves are opened, in order to prevent the blast from reaching the scrubber and condenser, on the other hand if at the end of a run the stack valve be opened before the 45 blast valve, the entire volume of good gas remaining in the machine will be blown out of the stack. Hence in order to avoid waste of this good gas, it is essential that the stack valve be opened a sufficient interval after the 50 opening of the blast valve to blow the good gas back into the scrubber and condenser. The stack valve must open, however, before any air can reach the scrubber and condenser.

55 The present invention provides an improved valve control mechanism for operating the several valves concerned in the operation of the machine from a central station with great ease of manipulation. Furthermore, the valve control mechanism is 60 equipped with interlocking devices which absolutely insure the operation of the several valves according to the proper successive order above stated. The invention additionally provides an auxiliary valve control

which permits opening of the generator blast valve just before the stack valve is opened, so as to conserve the good gas remaining in the machine after a run.

The valve control station 42 may be located at any suitable point in the machine or apparatus within convenient reach of an operator. Said station 42 comprises, preferably, a suitable rectangular casing 43 the top of which is closed by a cover-plate 44. 70 The cover-plate 44 is provided with a plurality of yokes 45 on which are pivoted a similar number of valve control levers 46, each lever being provided at its lower end with a horizontal portion 47 which is pivoted intermediate its ends at 48 between the two branches of a yoke 45. In the present invention, there are five levers 46 pivoted on a valve casing cover 44, said levers being a "purge" lever, an "up and down run" or 80 main valve lever, a "stack valve" lever, a "generator blast valve" lever, and a "carbureter blast valve" lever. The opposite ends of the horizontal portion 47 of each lever are connected by pivoted links 49, 50, with 85 the upper ends of valve stems 51, 52, which extend through glands 53, 54, fitted in the cover 44, into the interior of the valve casing 43. The lower ends of said valve stems 51, 52, are provided with valve heads 55, 56, 90 which work in vertical chambers 57, 58, formed in the valve casing 43. Preferably, said chambers 57, 58, are lined with bushings 59, 60. It will be understood that the valve stems 51, 52, of the several levers 46 95 are equipped with valve heads 55, 56, working in chambers 57, 58, all alike in construction. The several chambers 57, 58, of the valve casing 43 communicate with an inlet 100 chamber 61 extending across the tops of the chambers 57, 58, and the lower ends of said chambers 57, 58, all communicate with an outlet chamber 62 extending across the bottom of said vertical chamber 57, 58. The fluid under pressure, such as water, is admitted to the inlet chamber 61 by means of an inlet pipe 63 and the fluid from the outlet chamber 62 exhausts through an outlet pipe 64. Communicating with the several vertical chambers 57 through holes 65 110 formed in the bushing 59 are by-passes 66 which respectively lead to a series of pipes 67. Also communicating with the interiors of the several vertical chambers 58 through holes 68 in the bushings 60, are by-passes 69 115 which respectively lead to a series of pipes 70. The pipes 67, 70, of the carbureter blast lever 46 are respectively connected by means of suitable pipe unions with pipes 71, 72, 120 which lead respectively to the lower and upper ends of the carbureter blast valve operating cylinder 41; the pipes 67, 70, of the generator blast valve are connected by means of suitable pipe unions with line pipes 73, 74, leading respectively to lower 125

and upper ends of the generator blast valve operating cylinder 40; the pipes 67, 70, of the stack valve operating lever are connected by means of line pipes 75, 76, leading respectively to the upper and lower ends of the stack valve operating cylinder 30; the pipes 67, 70, of the up and down run valve-controlled lever are respectively connected by means of pipes 77, 78, with the lower and 10 upper ends of the up and down run valve operating cylinder 33; the pipes 67, 70, of the "purge" valve-operating lever are connected by means of line pipes 79, 80, with supplementary line pipes 81, 82. Line pipe 81 leads both to the lower end of the generator blast valve cylinder 38 and the upper end of the stack valve cylinder 30; line pipe 82 leads to the upper and lower ends of said respective cylinders 38, 30.

20 The several levers 46 are provided with an interlocking means for preventing operation of said levers in any other order than that in conformity with proper gas machine operations. For this purpose the several 25 levers are provided with interlocking lugs which compel their operation in a predetermined successive order and lock all of the levers against operation until the first lever concerned in the operation of a gas 30 making machine is operated to a position in accordance with the cycle set forth above. Referring now more particularly to Figs. 3 and 4, the purge lever 46 is provided with a horizontal lug 83 having at its end a cut-away portion 84 adapted to interlock with a complementary cut-away portion 85 of a lug 86 carried by the up and down run lever, whenever the up and down run lever is in any position other than the up-run position, 35 i. e. for directing the flow up through the generator. The up and down run lever is provided with a lug 87 having a cut-away portion 88 adapted to interlock with a cut-away portion 89 of a companion lug 90, carried by the stack valve lever, when the up and down run lever is in any position other than up-run position. Similarly the stack 40 valve lever is provided with a lug 91 having a cut-away portion 92 for interlocking the engagement with a cut-away portion 93 of a lug 94 carried by the generator blast valve, when the stack valve lever is in any position other than open position; in turn the generator blast lever is provided with 45 a lug 95 having a cut-away portion 96 for interlocking engagement with a companion cut-away portion 97 of a lug 98 carried by the carbureter blast lever whenever the generator blast lever is in any position other 50 than open position.

With the above interlocking lug construction the up and down run lever must be shifted to the up-run position before the stack valve lever can be shifted to open position; the generator blast lever cannot be 55 shifted to open position until the stack valve lever has been so shifted; and finally the carbureter blast lever cannot be shifted to open position until the generator blast lever has been so shifted. Conversely the carbureter blast lever must be closed before the generator blast lever; the generator blast lever must be closed before the stack valve lever; and the stack valve lever must be closed before the up and down run lever 60 can be shifted to the down-run position. The interlocks carried by the levers thus absolutely compel the proper cyclic operation of the gas making machine, i. e. when the blast is put on, the flow must be up 65 through the generator, the stack valve must be opened, the generator blast then opened and finally the carbureter blast. In taking off the blast and putting on the run the carbureter blast is closed, next the generator 70 blast, finally the stack valve is closed. With the stack valve lever in the closed position the up and down run lever can be shifted to up or down run position as desired, provided however the purge lever is also in the 75 closed position. As stated the purge lever controls the admission of fluid pressure to both the stack valve cylinder and the generator blast cylinder. This purge lever can only be shifted to the open position when 80 the up and down lever is in the up position. When the purge lever is opened, the generator blast first opened and shortly thereafter the stack valve closes, this operation taking place in the manner which will hereinafter appear. The effect produced by 85 operating the several levers 46 to the open or closed position is the same with regard to the several valve operating cylinders, which said lever respectively controls. Assuming that a lever 46 be shifted to a dotted line position shown in Fig. 5, the right hand piston head 55 thereof is depressed and the left hand piston head 56 thereof is elevated. This operation throws the by-pass 66 in communication with the inner chamber 51 and concurrently the by-pass 69 in communication with the outlet chamber 62. As a result pressure will flow from the inlet pipe 63 to the pipe 71, for example, leading to the lower end of the carbureter blast valve-operating cylinder 41 thereby causing the piston in said cylinder to elevate and open the valve. The pressure above the piston flows back through the pipe 72 to the by-pass 69 and thence to the outward chamber 62 through which it will be discharged through the outlet pipe 64. When the lever 46 is thrown to the reverse 95 position as indicated by the dotted lines in Fig. 5, the pipe 71 will be brought into communication with the outlet pipe 64 and the pipe 72 concurrently into communication with the inlet pipe 63 thereby lowering the piston in the carbureter operated cylinder 100

105

41 and closing said valve. The operation of the up and down run lever, stack valve lever and the generator blast lever is exactly the same as above described.

- 5 When the "purge" valve-lever is open fluid pressure flows from the inlet pipe 63 to the pipe 81 leading both to the lower end of the generator valve cylinder 40 and the upper end of the stack valve cylinder 30. 10 It will be noted the stack valve is made considerably heavier than the generator blast valve and hence more fluid pressure is required to operate the stack valve piston than the generator blast valve piston. As 15 a result, the generator blast valve opens slightly in advance of the stack valve. As soon as the generator blast valve piston is in extreme up position the pressure will flow to the stack valve cylinder 30 and effect an 20 immediate opening of said valve.

The invention also provides an auxiliary valve for permitting the carbureter blast to move slowly to full open position after the generator blast has been opened. In 25 some cases it is not desirable to turn on the full carbureter blast during the early stages of the blasting operation, for the reason that when the generator blast is first turned on the products from the generator chamber 30 are practically fully consumed and at this 30 time the effect of turning on the carbureter blast would be to reduce the temperature of the carbureter and the super-heater. Subsequently, however, partially consumed 35 products pass into the carbureter and it is desirable to burn these products in the carbureter in order to attain a complete heating effect. For effecting this result a leak valve, such as is shown in Fig. 6, is employed. The inlet 63 communicates by 40 means of a by-pass 99 with a valve chamber 100, the latter in turn communicating by means of a by-pass 101 with the pipe 67 leading to the pipe 71, through which pressure 45 flows to open the carbureter valve. Within the valve chamber 100 is a valve seat 102 provided with a conical passage-way 103. A needle valve 104 enters the conical passage-way 103. Said needle valve 104 is 50 screw-threaded, as at 105, in the valve chamber, and is also provided with an operating handle 106.

In the operation of the machine, the carbureter blast valve will be opened about 55 half-way of its travel by holding the carbureter blast valve operating lever in the open position until the carbureter blast valve is approximately one-half opened. This operating lever will then be moved into the central or neutral position, so that, so far as the 60 operating lever is concerned, there would be no tendency for the carbureter blast valve to open farther. While in this position, the air admitted through the half-open carbureter blast valve will be sufficient to consume

all of the combustible gas passing from the generator to the carbureter at the start of the blast. As the blast continues, however, the amount of combustible gas coming from the generator will gradually increase. By 70 turning the operating handle 106, the needle valve 104 may be adjusted to permit leakage of fluid pressure from the inlet 63 into the pipe 71, and this leakage will cause the carbureter blast valve to increase its 75 opening gradually in proportion to the increase in the amount of combustible gases coming over from the generator.

Whether or not this rate of increase in the blast valve opening is the proper amount 80 can be observed by the operator, who will note the color of the flame at the top of the stack. If the rate is not correct, he will increase or decrease the amount of leakage through the leak valve and after adjusting 85 this valve on one or two runs, the leak valve will be set in such position as to require very little adjustment through the remaining runs, throughout the day. The needle valve 104 permits adjustment of the leak 90 age through the valve seat 102 to a very fine degree, thereby permitting an operator to determine with great accuracy the gradual opening of the carbureter blast valve.

Within pipe 81 are check valves 107, 108, 95 permitting flow from pipe 79 into the branches of said pipe on both sides of pipe 79; also within pipe 82 are check valves 109, 110, permitting flow from both branches 100 of pipe 82 into pipe 80. These check valves prevent the operation of the purge lever from affecting the operation of the regular stack valve and generator blast valve pressure lines.

The invention is herein above set forth 105 as embodied in a particular form or construction, but may be variously embodied within the scope of the claims hereinafter made.

What is claimed is:

1. In a gas making apparatus, in combination: a gas generator; a stack adapted to communicate therewith; a blast pipe leading to said generator; a blast valve controlling the blast to the generator; a stack valve adapted to open the stack; and a unitary manually-controlled means for opening the blast valve and at an automatically determined interval thereafter opening the stack valve, whereby a blast through the 120 generator is maintained prior to the opening of said stack valve; substantially as specified.

2. In a gas making apparatus, in combination: a gas generator; a stack adapted 125 to communicate therewith; a blast pipe leading to said generator; a pressure-operated blast valve controlling the blast to the generator; a stack valve adapted to be opened by a relatively greater pressure than said 130

- blast valve; and means for admitting fluid pressure simultaneously to both said valves, whereby the stack valve opens at an automatically determined interval after the 5 opening of the aforesaid blast valve, to maintain a blast through the generator prior to the opening of said stack valve; substantially as specified.
3. In a gas making apparatus, in combination: a gas generator; a stack adapted to communicate therewith; a blast pipe leading to said generator; a pressure-operated blast valve controlling the blast to the generator; a stack valve adapted to be opened 10 by a relatively greater pressure than said blast valve; and a unitary manually-controlled means for admitting fluid pressure simultaneously to both said valves, whereby the stack valve opens at an automatically determined interval after the opening of the 15 aforesaid blast valve, to maintain a blast through the generator prior to the opening of said stack valve; substantially as specified.
4. In a gas making apparatus, in combination: a gas generator; a stack adapted to communicate therewith; a blast pipe leading to said generator; a pressure-operated blast valve controlling the blast to the generator; a stack valve adapted to be opened 20 by a relatively greater pressure than said blast valve; pressure-line connections for admitting fluid pressure simultaneously to both of said valves; and a single manually-controlled lever for controlling the flow of fluid pressure in said pressure-line connections, whereby the stack valve opens at an automatically determined interval after the opening of the aforesaid blast valve, to 25 maintain a blast through the generator prior to the opening of said stack valve; substantially as specified.
5. In a gas making apparatus, in combination: a gas generator; a stack adapted to communicate therewith; a blast pipe leading to said generator; a pressure-operated blast valve controlling the blast to the generator; a stack valve adapted to be opened 30 by a relatively greater pressure than said blast valve; pressure-line connections for admitting fluid pressure simultaneously to both of said valves; and means for controlling the flow of fluid pressure in said pressure-line connections, whereby the stack valve opens at an automatically determined interval after the opening of the aforesaid blast valve, to maintain a blast through the generator prior to the opening of said stack valve; substantially as specified.
6. In a gas making apparatus, in combination: a gas generator; a stack adapted to communicate therewith; a blast pipe leading to said generator; a blast valve controlling the blast to the generator; a stack valve 40 adapted to open the stack; valve means for selectively directing the flow up or down through said generator; and means, operable only when said valve means is set for up-flow through the generator, for opening the blast valve and at an automatically determined interval thereafter opening the stack valve; substantially as specified.
7. In a gas making apparatus, in combination: a gas generator; a stack adapted to communicate therewith; a blast pipe leading to said generator; a blast valve controlling the blast to the generator, a stack valve adapted to open the stack; valve means for selectively directing the flow up or down through said generator; and a unitary manually-controlled means, operable only when said valve means is set for up-flow through the generator, for opening the blast valve and at an automatically determined interval thereafter opening the stack valve; substantially as specified.
8. In a gas making apparatus, in combination: a gas generator; a stack adapted to communicate therewith; a blast pipe leading to said generator; a pressure-operated blast valve controlling the blast to the generator; a stack valve adapted to be opened by a relatively greater pressure than said blast valve; valve means for selectively directing the flow up or down through said generator; and means, operable only when said valve means is set for up-flow through the generator, for admitting fluid pressure simultaneously to both said valves, whereby the stack valve opens at an automatically determined interval after the opening of the aforesaid blast valve, to maintain a blast through the generator prior to the opening of said stack valve; substantially as specified.
9. In a gas making apparatus, in combination: a gas generator; a stack adapted to communicate therewith; a blast pipe leading to said generator; a pressure-operated blast valve controlling the blast to the generator; a stack valve adapted to be opened by a relatively greater pressure than said blast valve; valve means for selectively directing the flow up or down through said generator; and a unitary manually-controlled means, operable only when said valve means is set for up-flow through the generator, for admitting fluid pressure simultaneously to both said valves, whereby the stack valve opens at an automatically determined interval after the opening of the aforesaid blast valve, to maintain a blast through the generator prior to the opening of said stack valve; substantially as specified.
10. In a gas making apparatus, in combination: a gas generator; a stack adapted to communicate therewith; a blast pipe leading to said generator; a pressure-operated blast valve controlling the blast to the generator; a stack valve adapted to be opened by a relatively greater pressure than said blast valve; valve means for selectively directing the flow up or down through said generator; and a unitary manually-controlled means, operable only when said valve means is set for up-flow through the generator, for admitting fluid pressure simultaneously to both said valves, whereby the stack valve opens at an automatically determined interval after the opening of the aforesaid blast valve, to maintain a blast through the generator prior to the opening of said stack valve; substantially as specified.

erator; a stack valve adapted to be opened by a relatively greater pressure than said blast valve; pressure-line connections for admitting fluid pressure simultaneously to both said valves; valve means for selectively directing the flow up or down through said generator; and a single manually-controlled lever operable only when said valve means is set for up-flow through the generator, 10 for admitting fluid pressure to said pressure-line connections, whereby the stack valve opens at an automatically determined interval after the opening of the aforesaid blast valve, to maintain a blast through the 15 generator prior to the opening of said stack valve; substantially as specified.

11. In a gas making apparatus, in combination: an up and down run valve; a stack valve; a generator blast valve; a carburetor 20 blast valve; levers individually operable at will controlling the operation of said valves; and interlocking devices interposed between all of said levers for locking the stack valve lever, generator blast lever, and 25 carburetor blast lever against operation except when the up and down run lever is in up-run position; substantially as specified.

12. In a gas making apparatus, in combination: an up and down run valve; a stack 26 valve; a generator blast valve; a carburetor blast valve; levers individually operable at will controlling the operation of said valves; and interlocking devices interposed between said levers for releasing the stack 35 valve lever, the generator blast valve lever, and the carburetor blast valve lever successively in the order named, when the up and down run valve lever is in an up-run position; substantially as specified.

13. In a gas making apparatus, in combination: an up and down run valve; a stack 40 valve; a generator blast valve; a carburetor blast valve; levers individually operable at will controlling the operation of said 45 valves; and interlocking devices interposed between said levers and releasable by the

lever controlling the operation of the stack valve; substantially as specified.

14. In a gas making apparatus, in combination: a carburetor; a blast line leading to 50 said carburetor; a pressure-operated valve for opening and closing said blast line; fluid pressure lines for supplying pressure to operate said valve; a lever for controlling the flow in said pressure lines; and manually-controlled means for admitting fluid pressure to said line in quantities reduced 55 with respect to those supplied by operation of said lever.

15. In a gas making apparatus, in combination: a carburetor; a blast line leading to 60 said carburetor; a pressure-operated valve for opening and closing said blast line; a fluid pressure line for supplying pressure to open said valve; a second fluid pressure 65 line for supplying pressure to close said valve; a pressure supply source; a lever for connecting either of said fluid pressure lines with said pressure supply source; and a needle valve interposed between said pressure supply source and the fluid pressure 70 line for opening said valve.

16. In a gas making apparatus, in combination: a carburetor; a blast line leading to 75 said carburetor; a pressure-operated valve for opening and closing said blast line; a fluid pressure line for supplying pressure to open said valve; a second fluid pressure line for supplying pressure to close said valve; a pressure supply source; a lever for connecting either of said fluid pressure lines with said pressure supply source; and a manually-adjustable needle valve interposed 80 between said pressure supply source and the fluid pressure line for opening said valve. 85
